HEEL AND HEEL BLANK

Robert H. Goldbaum, Haverhill, Mass., assignor to
Richard Earle Goldbaum, Haverhill, Mass.

Application March 26, 1953, Serial No. 344,697

17 Claims. (Cl. 36—34)

The present invention relates to heels and heel blanks, and more particularly to wood heels and wood-heel blanks.

In the manufacture of wood heels, it is customary to cut the heel blanks from a hard, relatively expensive lumber board of rectangular cross section. The height of the board is usually slightly larger than the height of the heel to be manufactured therefrom, and the width of the board is slightly greater than the width of the heel-seat face of the heel. Heel blanks are formed from this board by cutting the board transversely along successively different angles, with alternate cuts disposed substantially parallel to each other, as described, for example, in United States Letters Patent No. 1,677,822, issued July 27, 1928, to N. L. Gulliford. The heels are then shaped from the heel blanks. A good deal of the lumber is wasted in the shaping operation, however, inasmuch as the lower portion of the ultimate heel is of much less width than the width of the heel blank.

An object of the present invention is to provide a new and improved heel blank that shall reduce the waste in lumber attendant upon the use of heel blanks of this character.

Another object is to provide a new and improved heel.

Still another object is to provide a novel laminated heel. In summary, the laminated heel of the present invention is constituted of main and auxiliary wood strips extending from the tread face to the heel-seat face of the heel and secured together near the heel-seat face with auxiliary wood-strip portions disposed symmetrically of the heel with respect to the main wood strip and extending longitudinally of the heel between the breast and the oppositely disposed face of the heel. Heel blanks adapted for the manufacture of such a laminated heel are hereinafter described in detail.

Other and further objects will be explained and will be more fully pointed out in the appended claims.

The invention will now be explained in connection with the accompanying drawing,

Figs. 1, 2 and 3 of which are perspective views illustrating three successive steps in the assembly and lamination of a main strip and auxiliary strips;

Fig. 4 is a side elevation illustrating the cutting of heel blanks from the assembled laminated strips of Fig. 3;

Fig. 5 is a perspective view, partly cut away to show details, illustrating the kiln-drying of the heel blanks;

Fig. 6 is a bottom elevation illustrating a turning operation;

Figs. 7 and 8 are side elevations illustrating breasting and heel-seat concaving operations;

Fig. 9 is a perspective view of a laminated heel constructed in accordance with a preferred embodiment of the present invention;

Figs. 10, 11 and 12 are similar views of modified laminated heel blanks;

Fig. 13 is a similar view of a modified laminated strip assembly; and

2

Fig. 14 is a side elevation, similar to Fig. 4, illustrating the cutting of the assembled laminated strips of Fig. 13 into heel blanks.

While the heel blanks and heels of the present invention may be formed in any desired manner, it is believed conducive to explanation and understanding of the properties and advantages of the heel blanks and heels to describe them in connection with their assembly and formation.

10 A main strip 1, as of expensive hard wood, having a width between substantially parallel oppositely disposed planar side walls 3 and 5 slightly larger than the ultimate width of the tread face of the heel to be manufactured, is assembled with auxiliary wood strips 7 and 9, as of waste lumber. The planar upper face 2 of the main strip 1 and the oppositely disposed bottom face are disposed in substantially parallel planes substantially orthogonal to the side walls 3 and 5. The auxiliary strips 7 and 9 are preferably, though, as later explained, not essentially, 20 right-triangular wedge-shaped strips, formed, for example, by diagonally cutting a rectangular board of dimensions too small for use in the formation of present-day heel blanks, and that would normally be wasted. The inner faces 13 and 11 of the respective auxiliary strips 7 and 9 are substantially planar to correspond to the planar side walls 3 and 5 of the main strip 1. The upper faces 17 and 15 of the respective auxiliary strips 7 and 9 are also substantially planar to correspond to the substantially planar upper face 2 of the main strip 1. The remaining faces 21 and 19 of the auxiliary strips 7 and 9 constitute the hypotenuse walls of the auxiliary strips. Glue 23, or any other suitable adhesive, is applied to the inner faces 13 and 11 of the auxiliary strips 7 and 9, Fig. 2, and to preselected portions of the side walls 3 and 5 of the main strip 1, as by a brush 8. The auxiliary strips 7 and 9 may then be clamped between a stationary vice jaw 6, Fig. 3, and a movable jaw 4, having clamping surfaces corresponding to the shape of the auxiliary strips 7 and 9, to secure the auxiliary-strip inner faces 13 and 11 to preselected upper portions or parts of the oppositely disposed side walls 3 and 5 of the main strip 1, with the upper planar faces 17 and 15 of the auxiliary strips 7 and 9 lying substantially in the plane of the upper face 2 of the main strip 1 and the hypotenuse walls 21 and 19 inclining or tapering toward the main strip, meeting the same along the edge 25, Fig. 3. The resulting welded laminated strip-assembly 1—7—9 is thus wider at the upper face 2—17—15 than at the intermediate region of the walls 3 and 5 below the edge 25 of 30 the auxiliary strips 7 and 9. In general, the direction of the grain of the auxiliary wood strips 7 and 9 will differ from that of the main strip, imparting increased strength to the laminated assembly. While the welding or gluing of the auxiliary strips 7 and 9 has been described, for 40 purposes of illustration, as effected by the brush application of glue and with the aid of a vice-clamping apparatus, it is to be understood that other well-known laminating processes and apparatus may be utilized to achieve the desired result.

45 The welded laminated strips 1—7—9 may then be transversely cut into laminated wood-heel blanks, as by placing them upon a periodically tiltable table 27, Fig. 4, similar to that described in the said Letters Patent, the original position of which is shown in solid lines, and the tilted position at 27' in dotted lines. A saw 29 cuts the laminated-strip assembly 1—7—9 transversely at successive regions, first along an incline 31, when the table 27 is in its solid-line position; next, along a differently inclined angle 33 when the table is inclined to the position 27'; 50 then, along the incline 31 parallel to the first-mentioned inclined cut 31; then, along the incline 33 parallel to the first-mentioned inclined cut 33; and so on, as the table 27

is tilted back and forth between the solid and dotted line positions. Similarly shaped wood heel blanks 10 substantially trapezoidal in longitudinal cross-section and Y-shaped in transverse cross-section will thus be formed. While intermediate wedges 12 between adjacent cuts 31 and 33 may be wasted in such an operation, it has been found that such waste is more than compensated for in the saving effected by the use of the blanks 10 of Fig. 4, as later discussed.

The laminated wood-heel blanks 10 may then be placed within trays 35, Fig. 5, and within a kiln 37. Steam heat, produced as by a hot water pipe or pipes 39 at the bottom of the kiln 37, rises through the kiln and passes out through upper ports 38, drying the blanks 10. Other curing or drying methods may, of course, be used, including chemical drying with alcohol, formaldehyde, chloroethylene and other chemicals, or natural seasoning, but kiln-drying speeds up production. The drying may be effected prior to cutting into blanks and the laminated strips may be varnished or covered with paraffin to prevent end bleeding. The kiln-dried laminated wood-heel blanks 10 are now ready for shaping into wood heels.

In Fig. 6, the blank 10 is shown held by a breast gauge 41 and turned as it is rotated with respect to a rotary cutter 43, as described, for example, in United States Letters Patent 2,038,534, issued April 28, 1936, to D. S. Bray. The turned convex portion of the heel, Fig. 9, then extends from the rear face of the main wood strip portion 1 of the heel blank 10, symmetrically forward along the rear and outer side faces of the auxiliary wood strip portions 9 and 7 of the heel blank. The turned blank 10 may then be clamped as at 45, Fig. 7, and breasted by a breasting cutter 47. The breast concavity so formed will extend from within the front face of the main wood strip portion 1 of the heel, Fig. 9, symmetrically forward on both sides of the main wood strip portion into the front face portions of the auxiliary strips 9 and 7. A cutter 49, Fig. 8, may then provide the heel-seat concavity, as described for example, in United States Letters Patent 2,065,645, issued December 29, 1936, to W. C. Brooks et al., the concavity extending from within the upper face 2 of the main strip portion 1 of the heel, Fig. 9, symmetrically upward on both sides of the main strip portion into the upper faces 17 and 15 of the auxiliary strip portions 7 and 9 of the heel blank.

As is evident from Figs. 6 to 9, much less wood is wasted in turning and forming the heel of the present invention from the Y-shaped blanks 10 than is the case where the heel blank is of substantially uniform width throughout. The auxiliary strips 7 and 9, moreover, may be formed from narrow strips of lumber that are today wasted or sold as scrap since they are not of sufficient dimensions to be used for making present-day heel blanks. The heel of the present invention, furthermore, is much stronger than present-day heels formed from solid pieces of lumber in view of the added strength imparted by the laminated structure and the before-mentioned cross-graining of the strips.

As before indicated, it is not necessary that the auxiliary strips 7 and 9 be of right-triangular wedge-shaped nature, though this deemed preferable for many applications of the invention. In Fig. 12, for example, the main strip portion 1 of a heel blank, constructed in accordance with the invention, is shown provided with L-shaped recesses 14 within which substantially trapezoidal auxiliary strips 7 and 9 may be seated with the narrower portions of the auxiliary strips secured to the bottom ledge of the L-shaped recesses 14 so that the heel blank is wider at its upper end than at an intermediate region of the blank. In Fig. 10, as another illustration, a single auxiliary strip 16 of width greater than that of the main strip 1 is secured to the upper face of the main strip 1, extending transversely preferably symmetrically beyond the opposite walls 3 and 5 in the form of a T. The auxiliary triangular wedges 7 and 9 are shown additionally provided in Fig.

11 to widen the blank near its intermediate portions. In the heel formed from the blanks of Figs. 10 and 11, the heel-seat concavity will extend from a centrally disposed region of the auxiliary strip 16 symmetrically upward on both sides thereof.

If it is desired to eliminate the waste of the before-mentioned wedge-shaped members 12, Fig. 4, additional auxiliary strips 7' and 9' may be secured, as previously described, near the bottom face of the main strip 1 to provide the preferably symmetrical X-shaped laminated strip-assembly of Fig. 13. In fabricating long lengths of laminated strips, finger joints 18 may be utilized to secure successive sections of main strips 1, while successive lengths of the thinner auxiliary strips 7, 9, 7', 9' may be secured by inclined abutting joints 20. When such a laminated assembly is placed upon a vertically tilttable table 27 and cut at successively different inclines of the table, as shown at 27 and 27', Fig. 14, there are no intermediate wedges wasted, such as the wedges 12 of Fig. 4. This is because the top of one heel blank and the bottom of the adjacent heel blank may be used as the heel seat, which was not possible with the unsymmetrical laminated arrangement of Fig. 4.

While the above-described heel blanks and heels are primarily useful and most advantageous in connection with wood, they are not restricted thereto, and other materials may, if desired, be employed.

Further modifications will occur to those skilled in the art and all such are considered to fall within the spirit and scope of the invention as defined in the appended claims.

What is claimed is:

1. A laminated wood-heel blank constituted of a main wood strip having substantially parallel opposite walls to which, near at least one of a pair of opposite faces of the main strip between the said walls, auxiliary wood strips are secured, the heel-seat face and the tread face of the laminated wood-heel blank being disposed in substantially parallel planes substantially orthogonal to the said walls, and the breast face and the rear face of the laminated wood-heel blank inclining transversely of the laminated wood-heel blank between the heel-seat face and the tread face.

2. A laminated wood-heel blank trapezoidal in longitudinal cross-section constituted of a main wood strip having substantially parallel opposite walls to which, near one face only of the main strip between the said walls, auxiliary wood strips are secured to provide greater width at the said one face than at the opposite face of the main strip between the said walls, the heel-seat face and the tread face of the laminated wood-heel blank being disposed in substantially parallel planes substantially orthogonal to the said walls, and the breast face and the rear face of the laminated wood-heel blank inclining toward each other transversely of the laminated wood-heel blank from the heel-seat face toward the tread face.

3. A laminated wood-heel blank trapezoidal in longitudinal cross-section constituted of a main wood strip having substantially parallel opposite walls to which, near each of the opposite faces of the main strip between the said walls, a pair of auxiliary strips is secured, the heel-seat face and the tread face of the laminated wood-heel blank being disposed in substantially parallel planes substantially orthogonal to the said walls, and the breast face and the rear face of the laminated wood-heel blank inclining toward each other transversely of the laminated wood-heel blank from the heel-seat face toward the tread face.

4. A laminated wood-heel blank trapezoidal in longitudinal cross-section constituted of a main wood strip having substantially parallel opposite walls to which, near both of a pair of opposite faces of the main strip between the said walls, auxiliary wood strips are secured to provide greater width at both faces than at an intermediate region of the main strip, whereby the laminated wood-heel

blank is substantially symmetrical with respect to the said intermediate region, the heel-seat face and the tread face of the laminated wood-heel blank being disposed in substantially parallel planes substantially orthogonal to the said walls, and the breast face and the rear face of the laminated wood-heel blank inclining toward each other transversely of the laminated wood-heel blank from the heel-seat face toward the tread face.

5. A laminated wood-heel blank trapezoidal in longitudinal cross-section constituted of a main wood strip having substantially parallel opposite walls to which, near both of a pair of opposite faces of the main strip between the said walls, substantially right-triangular wedge-shaped auxiliary strips are secured with the hypotenuse walls of the auxiliary strips inclining toward an intermediate region of the main strip to provide greater width at both faces than at the said intermediate region of the main strip, whereby the laminated wood-heel blank is substantially symmetrical with respect to the said intermediate region, the heel-seat face and the tread face of the laminated wood-heel blank being disposed in substantially parallel planes substantially orthogonal to the said walls, and the breast face and the rear face of the laminated wood-heel blank inclining toward each other transversely of the laminated wood-heel blank from the heel-seat face toward the tread face.

6. A laminated wood heel constituted of a main wood strip extending from the tread face to the heel-seat face of the wood heel and to opposite walls of which, near at least the heel-seat face, auxiliary wood strips are secured, the auxiliary wood strips being disposed symmetrically of the heel with respect to the main wood strip and extending longitudinally of the heel between the breast and the oppositely disposed face of the heel, and the concavity in the heel seat extending from within the main wood strip symmetrically upward on both sides of the main wood strip into the auxiliary wood strips.

7. A laminated wood heel constituted of a main wood strip extending from the tread face to the heel-seat face of the wood heel and to opposite walls of which, near the heel-seat face, auxiliary wood strips are secured, the main wood strip and the auxiliary wood strips having interlocking ledges, the auxiliary wood strips being disposed symmetrically of the heel with respect to the main wood strip and extending longitudinally of the heel between the breast and the oppositely disposed face of the heel, and the concavity in the heel seat extending from within the main wood strip symmetrically upward on both sides of the main wood strip into the auxiliary wood strips.

8. A laminated wood heel constituted of a main wood strip extending from the tread face to the heel-seat face of the wood heel and to opposite sides of which near at least the heel-seat face, auxiliary wood strips are secured, the breast concavity extending from within the front face of the main wood strip symmetrically forward on both sides of the main wood strip into the front faces of the auxiliary wood strips, the turned convex portion of the heel extending from the rear face of the main wood strip symmetrically forward along the rear and outer side faces of the auxiliary wood strips, and the concavity in the heel seat extending from within the upper face of the main wood strip symmetrically upward on both sides of the main wood strip into the upper faces of the auxiliary wood strips.

9. A laminated wood-heel blank constituted of a main wood strip having substantially parallel opposite walls and a pair of opposite faces between the said walls, auxiliary wood-strip means secured to the main strip near at least one of the said faces thereof to provide greater width at the said one face than at an intermediate region of the main strip, the heel-seat face and the tread face of the laminated wood-heel blank being disposed in substantially parallel planes substantially orthogonal to the said walls, and the breast face and the rear face of the

laminated wood-heel blank inclining transversely of the laminated wood-heel blank between the heel-seat face and the tread face.

10. A laminated wood-heel blank trapezoidal in longitudinal cross-section and T-shaped in transverse cross-section constituted of a main wood strip having substantially parallel opposite walls and a pair of opposite faces between the said walls, an auxiliary wood strip of greater width than the main wood strip secured to one of the said faces and extending transversely beyond the said walls to provide greater width at the said one face than at the opposite face of the main strip between the said walls, the heel-seat face and the tread face of the laminated wood-heel blank being disposed in substantially parallel planes substantially orthogonal to the said walls, and the breast face and the rear face of the laminated wood-heel blank inclining toward each other transversely of the laminated wood-heel blank from the heel-seat face toward the tread face.
11. A laminated wood-heel blank trapezoidal in longitudinal cross-section constituted of a main wood strip having substantially parallel opposite walls and a pair of opposite faces between the said walls, substantially right-triangular wedge-shaped auxiliary strips secured to the said walls near one of the said faces with the hypotenuse walls of the auxiliary strips inclining toward an intermediate region of the main strip, a further auxiliary strip of width greater than the width of the secured main and wedge-shaped auxiliary strips secured to the said one face and extending transversely beyond the said wedge-shaped auxiliary strips to provide greater width at the said one face than at the opposite face of the main strip between the said walls, the heel-seat face and the tread face of the laminated wood-heel blank being disposed in substantially parallel planes substantially orthogonal to the said walls, and the breast face and the rear face of the laminated wood-heel blank inclining toward each other transversely of the laminated wood-heel blank from the heel-seat face toward the tread face.
12. A laminated wood heel constituted of a centrally disposed main strip and auxiliary wood strips extending from the tread face toward the heel-seat face of the wood heel and secured together near the heel-seat face with auxiliary wood-strip portions disposed symmetrically of the heel with respect to the main wood strip and extending longitudinally of the heel in the direction between the breast and the oppositely disposed face of the heel.
13. A laminated wood heel constituted of a main wood strip to the upper face of which an auxiliary wood strip of greater width is secured symmetrically of the heel with respect to the main strip and extending longitudinally of the heel between the breast and the oppositely disposed face of the heel, and the concavity in the heel seat extending from a centrally disposed region within the auxiliary wood strip symmetrically upward on both sides thereof.
14. A laminated wood heel constituted of a main wood strip to opposite walls of which, near the heel-seat face a pair of auxiliary wood strips are secured, the auxiliary wood strips being disposed symmetrically of the heel with respect to the main wood strip and extending longitudinally of the heel between the breast and the oppositely disposed face of the heel, a further auxiliary wood strip secured to the upper faces of the pair of auxiliary wood strips and the main wood strip, and the concavity in the heel seat extending from a centrally disposed region within the further auxiliary wood strip symmetrically upward on both sides thereof.
15. A laminated wood-heel blank trapezoidal in longitudinal cross-section constituted of a main wood strip having substantially parallel opposite walls to which, near at least one of the opposite faces of the main strip between the said walls, a pair of auxiliary strips is secured, the heel-seat face and the tread face of the laminated wood-heel blank being disposed in substantially parallel planes substantially orthogonal to the said walls, and the breast

face and the rear face of the laminated wood-heel blank inclining toward each other transversely of the laminated wood-heel blank from the heel-seat face toward the tread face.

16. A laminated wood-heel blank constituted of a main wood strip having substantially parallel opposite walls to which, near at least the upper face of the main strip between the said walls, auxiliary wood strips are secured, the heel-seat face and the tread face of the laminated wood-heel blank being disposed in substantially parallel planes substantially orthogonal to the said walls, and the breast face and the rear face of the laminated wood-heel blank inclining transversely of the laminated wood-heel blank between the heel-seat face and the tread face.

17. A laminated wood-heel blank constituted of a main wood strip having substantially parallel opposite walls to

5 which, near each of the opposite faces of the main strip between the said walls, auxiliary wood strips are secured, the heel-seat face and the tread face of the laminated wood-heel blank being disposed in substantially parallel planes substantially orthogonal to the said walls, and the breast face and the rear face of the laminated wood-heel blank inclining transversely of the laminated wood-heel blank between the heel-seat face and the tread face.
